CLAIM

The ornamental design for a hanging sign, as shown and described.

DESCRIPTION

FIG. 1 is a perspective view of a hanging sign, showing our new design;

FIG. 2 is a front view thereof;

FIG. 3 is a back view thereof;

FIG. 4 is a left end elevational view thereof;

FIG. 5 is a right end elevational view thereof;

FIG. 6 is a top plan view thereof; and,

FIG. 7 is bottom plan view thereof.

The broken lines in the drawings depict portions of the hanging sign that form no part of the claimed design.
